CLAIM

The ornamental design for a toy teeth set, as shown and described.

DESCRIPTION

FIG. 1 is a perspective view of the first part and the second part assembled together of a toy teeth set, showing my new design;

FIG. 2 is a perspective view of the first part and the third part assembled together of the toy teeth set;

FIG. 3 is a perspective view of the first part of the toy teeth set;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a perspective view thereof, shown in an alternative configuration;

FIG. 12 is a perspective view of the second part of the toy teeth set;

FIG. 13 is another perspective view thereof;

FIG. 14 is a front view thereof;

FIG. 15 is a rear view thereof;

FIG. 16 is a left side view thereof;

FIG. 17 is a right side view thereof;

FIG. 18 is a top plan view thereof;

FIG. 19 is a bottom plan view thereof;

FIG. 20 is a perspective view thereof, shown in an alternative configuration;

FIG. 21 is a perspective view of the third part of the toy teeth set;

FIG. 22 is another perspective view thereof;

FIG. 23 is a front view thereof;

FIG. 24 is a rear view thereof;

FIG. 25 is a left side view thereof;

FIG. 26 is a right side view thereof;

FIG. 27 is a top plan view thereof;

FIG. 28 is a bottom plan view thereof;

FIG. 29 is a perspective view thereof, shown in an alternative configuration; and,

FIG. 30 is a front view of three parts of the toy teeth set.

1 Claim, 30 Drawing Sheets
